(57) **CLAIM**

I claim the ornamental design for the luminary four-sided boxed light fixture, as shown and described.

DESCRIPTION

FIG. 1 is a front perspective view of the luminary four-sided boxed light fixture according to the present invention; and, FIG. 2 is a top view of the luminary four-sided boxed light fixture according to the present invention.

The broken lines immediately adjacent the shaded areas represent the boundaries of the claimed design and form no part thereof.
